UNITED STATES PATENT OFFICE.

JOHN R. ROSE AND EDWARD L. CALEY, JR., OF PHILADELPHIA, PENNSYLVANIA, ASSIGNORS TO COX, WHITEMAN & COX, OF SAME PLACE.

DESIGN FOR RANGE-STOVE.

Specification forming part of Design No. 6,134, dated September 10, 1872.

Specification describing a Design for Range-Stoves, invented by JOHN R. ROSE and EDWARD L. CALEY, Jr., of the city of Philadelphia, in the State of Pennsylvania.

The nature of our design is fully represented in the accompanying photographic illustration and sectional drawing, to which reference is made.

Figure 1 represents a perspective view of the range-stove complete; and Figs. 2, 3, 4, 5, respective transverse sections of the moldings of the top plate, bottom plate, hearth, and ends, and of the door-plates.

A, is the molding around the outer edge of the top plate a'; B, the edge-molding around the front and sides of the hearth b' of the bottom plate, (see Fig. 3;) C, the edge-molding on the right and left hand sides of the bottom plate, (see Fig. 4;) D, the edge-molding of the door d' of the oven, and of the door d'' of the fire-box, (see Fig. 5.) The panel of the doors d' and d'', and also the panels of the end plates d''' of the range-stove, Fig. 1, are ornamented by bas-relief, straight lines v v, crossing each

other at the four corners of the panel by the intervening quarterfoils w w and by the central figure x, as shown in Fig. 1.

We claim as our invention of a design for the range-stove shown—

1. The edge-molding A of the top plate a', as shown in Figs. 1 and 2.
2. The edge-molding B of the hearth b' of the bottom plate, as shown in Figs. 1 and 3.
3. The edge-molding C of the right and left hand edges of the bottom-plate, as shown in Figs. 1 and 4.
4. The edge-molding D of the doors of the oven and of the fire-box, as shown in Figs. 1 and 5.
5. The bas-relief ornamentations v v, w w, and x on the panels of the doors d' and d'', and on the panel d''' of the sides of the range-stove, as shown in Fig. 1.

JOHN R. ROSE.
